UNITED STATES PATENT OFFICE.

EDWARD H. JUNGCLAS, OF CINCINNATI, OHIO.

AIRCRAFT-ANCHOR.

1,316,620.

Specification of Letters Patent. Patented Sept. 23, 1919.

Application filed September 14, 1917. Serial No. 191,369.

To all whom it may concern:

Be it known that I, EDWARD H. JUNGCLAS, a citizen of the United States, and a resident of Cincinnati, in the county of Hamilton 5 and State of Ohio, have invented certain new and useful Improvements in Aircraft Anchors, of which the following is a specification.

My invention relates to means for holding 10 aircrafts, especially aeroplanes, during the operations preliminary to flight after the propeller is started and exerting a pull on the craft.

The object of my invention is to enable the 15 aviator to dispense with assistants during such time, so that flight may be effected at any time or any place wherever the craft may have alighted.

My invention consists in the combination 20 of parts and in the details of construction and arrangement of parts as will herein-after be more fully described and claimed.

In the drawings:

Figure 1 is a side elevation of an aeroplane anchored by a device embodying my 25 invention;

Fig. 2 is a partial similar view somewhat enlarged and showing a modification of my invention;

Fig. 3 is a view similar to Fig. 2 showing another modification of my invention;

Fig. 4 is an enlarged detail partly in longitudinal section of the yieldable connection and indicating means of Fig. 2.

Fig. 5 is a vertical longitudinal cross-section of the latch.

As shown in Fig. 1, a tension element 1 has a pivotal connection or hinge 2 on the lower side of the body of the aeroplane on 40 the fore-and-aft center line thereof. This tension element 1 extends downwardly and rearwardly and on its free end has a releasable connecting device or latch 3 which is connected to a stake 4 driven into the ground and preferably considerably slanted backwardly. This connecting device or latch 3 is released by the aviator inside the aeroplane as by the treadle 5 connected to the latch by a cable 6 passing downwardly and 50 rearwardly and then more directly downwardly over a sheave 7 in the lower part of the aeroplane body.

The preferred specific construction of the 55 releasable connecting device 3 is better shown in Figs. 2 and 3.

In Figs. 2 and 4, the tension element com-

prises the forward tubular member 8 and the member 9 sliding in the member 8 and held to the member 8 by a tension spring 10 inside the member 8. A pointer 11 on 60 the member 9 extends out through a longitudinal slot 12 in the member 8, and as it slides along, graduations 13 along the edge of the slot on the outside of the member 8, indicates the pull of the aeroplane, so that an 65 operator may determine the tractive effort of the craft as an indication of when to release it. In the example of Fig. 3, the tension element is a flexible cable 17.

While the tension elements are thus modified, the releasable connecting devices 3 are preferably the same; consisting as best shown in Fig. 5, of a bar 14 suitably connected to the free end of the tension element and extending up therefrom and having two jaws 15 extending back opposite the tension element connection and having at its upper end a backwardly extending lug 16. Through this lug 16 and through the jaws 15 projects a plunger 17 which is normally held projected across the space between the jaws 15 by a helical spring 18 around the plunger and compressed between a collar 19 fixed on the plunger and the lower side of the lug 16. The stake 4 has 85 an eye-bolt 20 through it with its eye projecting forward between the jaws 15 and embracing the plunger 17.

Thus if the plunger 17 is withdrawn upwardly out of the eye of the eye-bolt 20, 90 the tension element is released from the stake leaving the aeroplane free to travel forward.

The upper end of the plunger 17 has an eye 21 in which the cable 6 is fastened, 95 which cable passes up over the sheave 7 to the treadle 5 as hereinbefore described, and as fully shown in Fig. 1. Thus, it will be seen that when the aviator pushes forward on the treadle 5, the plunger 17 is drawn 100 upward and the operation takes place as just described.

Where the tension element is rigid, as in Fig. 1, or consists of two rigid elements telescoping as in Fig. 2, I prefer to provide a 105 torsional spring 22 around the pivot of the hinge 2 where the tension element is hinged to the aeroplane body; one end 23 of this spring engaging a projection 24 a short distance back on the tension element, (Fig. 2) 110 and the other end 25 of the spring engaging with the under side of the aeroplane body.

Where the flexible tension element 1' is used as in Fig. 3, a second cable 26 may be provided connected to an eye 27 on the upper end of the bar 14 passing upward and forward over a sheave 28 journaled in the lower part of the aeroplane body, and connected to the rear end of a long tension spring 29 which has its forward end connected to a lug 30 fixed in the lower part 10 of the aeroplane body. Thus, the connecting device 3 is pulled up as soon as it is released from the stake 4, and the flexible tension element 1' is carried with it up close to the bottom of the aeroplane body.

15 In any instance, it will be seen that the aviator is enabled to get away without the assistance of others to hold the aeroplane back after he has started the motor and during the time the motor is gaining speed and 20 the aviator is attending to other matters which must be attended to after the starting of the motor and before actual starting of the aeroplane, in order to insure the safety of the craft and its occupants.

25 Having fully described my invention, what I claim as new and desire to secure by Letters Patent is:

1. In an aircraft anchor, elongated tension means having one end part hinged to 30 the craft, and extending rearwardly and downwardly, a manually releasable fastener on the opposite end part of said tension means, and means for automatically swinging said tension means up toward the craft 35 when said fastener is released.

2. In an aircraft anchor, a tension element, means to connect one end of said element to the craft, and means to connect the other end of said element to the ground, one 40 of said means comprising a bar with projections, a plunger sliding in said projections, an eye engaging around said plunger, and a spring detachably holding said plunger in position for engagement of said eye.

45 3. In an aircraft anchor, a retaining element comprising two members yieldably connected, means to connect one end of said element to the craft, means to connect the other end of said element to the ground, a 50 scale of graduations on one of said mem-

bers, a pointer on the other member to indicate by said scale the pull of said craft on said retaining element, one of said means for connecting said retaining element being releasable during any position of said pointer along said scale, and means extending from said releasable means inside the craft and accessible inside said craft for releasing said connecting means.

4. In an aircraft anchor, a retaining element comprising a tubular member, and another member sliding in the tubular member, a tension spring connecting this other member to the tubular member inside said tubular member, this other member carrying a pointer, and said tubular member having a slot through which said pointer extends, and a series of graduations along said slot to indicate the degree of extension of said members, a hinge connecting one end of one of said members to an under side of 70 said craft, a torsional spring in said hinge having one end engaging said member, and the other end engaging said craft to normally hold said retaining element up close to said craft, a bar fixed on the end of the 75 other one of said members of said retaining element and extending up toward said craft therefrom, jaws extending from said bar, an eye fixed to the ground and lying between said jaws, a plunger sliding through one of 80 said jaws into said eye, a helical spring around said plunger along the upper part of said bar, a lug near the upper end of said bar, a collar fixed on said plunger, said helical spring being compressed between said 85 collar and said lug and yieldably holding said plunger in said eye, said plunger extending through said lug and having an eye thereabove, a cable fixed in said eye and extending up into the body of said craft, and 90 manipulating means inside said craft with the other end of said cable attached thereto, whereby said plunger may be withdrawn 95 by an operator inside said craft.

EDWARD H. JUNGCLAS.
